MAKE-UP BOX

Sarah Lieberman, Waterbury, Conn., assignor to
 Chase Brass & Copper Co. Incorporated, Waterbury, Conn., a corporation of Connecticut

Application October 23, 1936, Serial No. 107,197

2 Claims. (Cl. 240—6.45)

This invention relates to improvements in make-up boxes, and more particularly to make-up boxes having light-means and a mirror in conjunction therewith.

One object of this invention is to provide an improved make-up box having a mirror and light-supplying means in conjunction therewith, the light-supplying means being connected to an electric cable extending outside the box for connection to a power line.

Another object of this invention is to provide an improved make-up box having a mirror in conjunction therewith, and power-supplied light-means with ventilation-means to avoid excessive rise of temperature adjacent the light-means.

Another object of this invention is to provide an improved make-up box formed of simple elements readily manufactured and readily assembled to produce an attractive construction at minimum cost.

With the above and other objects in view, as will appear to those skilled in the art from the present disclosure, this invention includes all features in the said disclosure which are novel over the prior art.

In the accompanying drawing, in which one way of carrying out the invention is shown for illustrative purposes:

Fig. 1 is a side elevation with the cover in open position of a make-up box constructed in accordance with this invention;

Fig. 2 is an end view of the make-up box shown in Fig. 1;

Fig. 3 is a top plan view of the make-up box shown in Figs. 1 and 2;

Fig. 4 is a transverse section on line 4—4 of Fig. 3;

Fig. 5 is a longitudinal section on line 5—5 of Fig. 3; and

Fig. 6 is a longitudinal sectional view on line 6—6 of Fig. 3.

In the description and claims, the various parts are identified by specific names for convenience, but they are intended to be as generic in their application as the prior art will permit.

Referring to the drawing, the make-up box 10 preferably has an illumination compartment 11 and a cosmetic compartment 12. The make-up box 10 is preferably formed of any suitable molded composition material and preferably has an integrally-molded partition 13 to form the separation wall between the compartments 11 and 12.

The cosmetic compartment 12 may contain any suitable cosmetics such, for example, as lipstick,

rouge, compact and eyebrow pencil. Or, instead of the foregoing materials, it may be provided with loose powder and a powder puff.

The box 10 preferably has supporting-feet 14 which raise the under-side of the box above the level of the surface upon which the box rests. The illumination compartment 11 preferably has a plurality of ventilation holes or openings 15 through the bottom of the compartment, and also has integrally-molded bracket-locating ribs 16 and light-transmission-plate supporting-ribs 17 and a cable-entrance hole or passage 18. The end-wall 19 of the box 10, which also forms one wall of the illumination compartment 11, is provided with a hinge-construction 20, at which is hinged a cover 21 having the inner surface provided with a mirror or formed with a mirror-surface 22.

An electric socket or light-bulb socket 23 has a threaded shank 24 extending through and fastened to an upstanding arm-portion 25 of an L-shaped bracket 26 by means of a nut 27 threaded on the screw-threaded shank 24. The lower or horizontal arm-portion 28 of the bracket 26 is located between the bracket-locating ribs 16 and secured firmly in place by means of the screw 29 which extends through the bottom 30 of the illumination compartment. A light-bulb 31 is detachably screw-threaded in the socket in a usual manner. An electric cable 32 extends through the hole 18 and supplies electric power to the light-socket from any suitable power-supply, such as the usual household lighting current.

A light-transmission plate 33 of general rectangular form rests upon the supporting-ribs 17, but preferably has a loose fit in the compartment to provide air-exit ventilation around the lateral edges of the plate. The plate 33 also preferably has a large hole or opening 34 which serves both to provide air-exit ventilation and also to provide for the passage therethrough of a switch-operating threaded-shank 35 carrying a switch-button 36 for operation by rotation. The light-transmission plate 33 may be made of glass or any suitable light-transmitting material and preferably is made to have a translucent or ground-glass effect to constitute light-diffusion means for the light coming from the electric bulb 31. The electric bulb 31 in actual practice has been found satisfactory when consuming seven watts of current. However, this amount of power tends to cause a substantial amount of heat which, if completely trapped in the illumination compartment, would tend to unduly

raise the temperature thereof with risk of injury to the compartment or adjacent parts.

By providing air-ventilation means, as shown, whereby air can pass beneath the box 10 by virtue of the bottom thereof being spaced by means of the supporting-feet 14 above the supporting-surface on which the box rests, air can pass upwardly through the ventilation-holes 15 in the bottom 30 of the illumination compartment, absorb heat generated by the light-bulb, and thence proceed upwardly through the hole 34 in the light-transmission plate 33, and also around the edges of the loosely-fitting light-transmission plate 33, thus maintaining the illumination compartment at a sufficiently-low temperature to avoid unsatisfactory operation.

The invention may be carried out in other specific ways than that herein set forth without departing from the spirit and essential characteristics of the invention, and the present embodiment is, therefore, to be considered in all respects as illustrative and not restrictive, and all changes coming within the meaning and equivalency range of the appended claims are intended to be embraced therein.

I claim:

1. A make-up box comprising: a hinged cover with an inner mirror-surface; a cosmetic compartment; and an illumination compartment ad-

10 jacent the hinge of said hinged cover and including: an electric light-bulb socket; an electric power-cable connected to said socket and extending through a hole in said box and designed and adapted to be connected to an electric-power connection exterior of said box; a light-transmission plate at the top of said compartment and overlying said socket and provided with a hole; a switch-operating member extending through said hole, said hole being also adapted to air-exit ventilation; and ventilation air-entrance means below said plate.

15 2. A make-up box comprising: a hinged cover with an inner mirror-surface; a cosmetic compartment; and an illumination compartment ad- 15 jacent the hinge of said hinged cover and including: an electric light-bulb socket; an electric power-cable connected to said socket and extending through a hole in said box and designed and adapted to be connected to an electric-power 20 connection exterior of said box; a light-transmission plate at the top of said compartment and overlying said socket and providing air-exit ventilation past its edge, and also provided with a hole; a switch-operating member extending 25 through said hole, said hole being also adapted to air-exit ventilation; and ventilation air-entrance means below said plate.

SARAH LIEBERMAN.
